UNITED STATES PATENT OFFICE.

ABRAHAM A. SHOBE AND WILLIAM EMBLEY, OF JERSEYVILLE, ILLINOIS.

CURRENT-COLLECTING DEVICE FOR ELECTRIC-RAILWAY SYSTEMS.

SPECIFICATION forming part of Letters Patent No. 766,399, dated August 2, 1904.

Application filed September 26, 1903. Serial No. 174,811. (No model.)

To all whom it may concern:

Be it known that we, ABRAHAM A. SHOBE and WILLIAM EMBLEY, citizens of the United States, residing at Jerseyville, in the county 5 of Jersey and State of Illinois, have invented a new and useful Current-Collecting Device for Electric-Railway Systems, of which the following is a specification.

This invention relates to certain improvements in current-collecting devices adapted especially for use in connection with that general class of electric-railway systems in which the current-conductors are arranged in an underground conduit.

15 The principal object of the invention is to provide a novel form of current-collector in which the movable conducting members will be at all times held firmly in engagement with the stationary conductors without regard 20 to uneven movement of the car or any irregularities in the road-bed or variations in position of the conductors.

A further object of the invention is to provide a novel form of support whereby the car 25 may be free to vibrate both vertically and laterally without in any manner disturbing the position of the moving contacts.

With these and other objects in view, as will more fully hereinafter appear, the invention 30 consists in the novel construction and arrangement of parts hereinafter described, illustrated in the accompanying drawings, and particularly pointed out in the appended claims, it being understood that various 35 changes in the form, proportions, size, and minor details of the structure may be made without departing from the spirit or sacrificing any of the advantages of the invention.

In the accompanying drawings, Figure 1 is 40 a transverse sectional elevation of sufficient of an electric-railway system to illustrate the application thereto of a current-collecting device constructed and arranged in accordance with the invention. Fig. 2 is an elevation of 45 the same. Fig. 3 is a detail perspective view of the upper portion of the hanger for supporting the contact-blocks. Fig. 4 is a similar view of the current-collector proper.

Similar numerals of reference are employed

to indicate corresponding parts throughout 50 the several figures of the drawings.

In the drawings, 1 designates an ordinary form of conduit comprising suitable vertical plates 2 and top members 3, the latter being slightly spaced in order to form the usual slot 55 for the passage of the slot-bar.

Arranged within the conduit are two brackets 4 and 5, the bracket 4 serving as a support for the positive conductor and the bracket 5 supporting the negative or return 60 conductor.

The positive conductor 6 is in the form of a T-bar supported at suitable intervals by T-shaped spindles 7, the lower horizontal web of which extends into grooves 8, formed in 65 the adjacent walls of a bar or supporting-bars 9. The bars 9 are of wood or similar non-conducting material that may be coated with a suitable preserving paint or compound in order to prevent saturation, and at suitable 70 intervals these bars are supported by the brackets 4, both the bars and the conductor 6 being practically continuous, although they may be sectional, if desired. It is intended that the main conductor 6 be jointless from 75 end to end or at least in the form of a continuous strip for considerable distance, as from one crossing to another, the supports 7 sliding freely in the grooves 8 in order to permit the necessary expansion and contraction and consequent alteration in the length of the conductors due to thermal changes. The brackets serve also as supports for feed-wires 10, which in the present instance are shown as 80 inclosed in suitable insulating-tubes, these 85 wires serving as feeders to the main conductor and being connected thereto in any desired manner, such method of distribution and connection being well known to those skilled in the art. The return-conductor 11 is also 90 in the form of a T-shaped rail or bar that is held between two wooden strips 12, supported by the brackets 5 at suitable intervals. The bar 11 is formed of iron or some other metal suitable for the purpose and is connected at 95 intervals to a main return-conductor 13 by bonding-plates 14, the conductor proper being insulated and armored, as indicated at 16

in Fig. 1. The construction of the return-conductor is such as to permit of free longitudinal movement due to expansion and contraction, so that both conductors may be freely moved without the slightest danger of warping or twisting when subjected to varying thermal conditions.

The main frame of the current-collector comprises a block 14', preferably formed of wood or other material of suitable character, said block being connected at a central point to a slot-bar 15, that extends down through a centrally-disposed opening formed in the block, and the connection between the two is formed by a bolt 16', so arranged as to permit of some slight lateral and longitudinal play and slight pivotal movement of the block with respect to the slotted bar.

To the opposite sides of the block are secured brackets 17, having depending outer flanges 18, and to these brackets are secured angle-bars 19, the vertical webs of which are parallel with the flanges 18, and said webs and flanges serve to restrict lateral play of the contact-blocks 19', that are held in frictional engagement with the current-conductor. Each of the blocks 19' is connected to the lower end of a binding-post 20, to the upper end of which is secured a current-conducting wire 21, leading to the motor on the car, the wire being held in place by the usual binding-screw 22. Each of the blocks also carries a pair of leaf-springs 23, the opposite ends of which bear against the lower surface of the brackets 17, while the intermediate portions of the springs are rigidly secured to blocks 24, having dovetail or beveled sides that fit in correspondingly-shaped recesses formed in the upper portions of the block.

At a point midway between the brackets on each side of the block is arranged a bracket or arm 25, having an opening through which the binding-post 20 passes and by which it is guided, so that the contact-block may be moved freely up and down in following any irregularities of the conductor or the main body of the collecting device may be moved up or down as the car vibrates in following any irregularities of the road-bed.

The slot-bar 15 is provided at its opposite edges with vertical openings 30 for the passage of the current-conducting wires, so that the wires are shielded from contact with the walls of the conduit-slot.

Secured to the truck-bolster 31 or to other convenient points of the car or other vehicle is a hanger 32, preferably formed in two parts united by suitable rivets or similar securing devices and provided at its lower end with sockets for the reception of a hinged pintle 33, that forms a support for a hollow bar 35, that is preferably of rectangular form in cross-section and serves as a guide for a vertically-disposed bar 36, the lower end of which is hinged to the top of the slot-bar 15.

Near the upper end of the hollow bar 35 is a transversely-extending opening 37, and disposed within the opening is a spring and spring-casing of the character best shown in Fig. 3. The spring-casing comprises a lower cup 38, having dependent lugs 39, arranged one on each side of the upper portion of the bar 36 and secured thereto by a suitable bolt 37. The base of the cup has an upwardly-projecting pin 40, forming a lower guide for a compression-spring 41. The upper member of the spring-casing is in the form of an inverted cup, as indicated at 42, and fits telescopically over a cup-shaped member 38, and the upper casing member is provided with a screw 43, the lower end of which projects within the cup and forms a guide for the upper end of the spring. The upper end of the screw 43 is adapted to a threaded opening in the bar 35 and by turning said screw the cup-shaped member 42 may be depressed or may be riveted in order to adjust the stress of the spring to any desired extent, and thus gradually adjust the degree of frictional contact between the blocks and the current-collector and the conductors within the conduit. The spring serves to force the contact-blocks into engagement with the current-conductors, and the lower portion of the spring-cup is therefore normally playing freely in the opening 37. Should the contact-blocks leave the current-conductors or the lower portion of the slot-bar drop from any cause, the lugs 39 of the bar 36 will come into contact with the lower wall of the opening 37 and prevent excessive downward movement of the parts.

It will be observed that the comparatively loose connection between the car and the current-collector will permit free lateral as well as vertical movement of the car without in any manner disturbing the position of the contact-blocks and that under all circumstances the springs will act to force the contact-blocks into constant engagement with the conductors.

It is of course apparent that rollers may be substituted for the friction-blocks shown in the drawings, and as this is a common and well-known expedient in the art illustration of this particular detail is not considered necessary.

Having thus described the invention, what is claimed is—

1. In an electric-railway system, having stationary electrical conductors, a loosely-mounted current-collector free to accommodate itself to variations in the relative positions of the conductors and the traffic-rails, said collector including a block or body portion, a slot-bar loosely connected to the slot to permit limited rocking and pivotal play, brackets carried by the block, and loosely-mounted contacts free for vertical and pivotal movement with respect to the brackets, said brackets serving as means for limiting the independent play of the contacts.

2. In a current-collector, the combination with a block or body portion, of projecting guiding-brackets, contact-blocks guided by the brackets and held thereby from excessive lateral movement, binding-posts carried by the contact-blocks, binding-post-guiding brackets carried by the block and permitting free vertical play thereof, springs arranged between the blocks and the brackets and tending to force the blocks into engagement with the current-conductors, a slot-bar connected to the block, and current-conducting wires connected to the binding-posts, substantially as specified.
3. In a current-collector, a bar or block of insulating material, spaced brackets arranged in pairs on opposite sides of the block and having depending flanges, angle-bars secured to the brackets and having vertically-disposed webs, contact-blocks guided between the flanges and webs, springs tending to force the contact-blocks away from the brackets, binding-posts secured to the contact-blocks and forming a pivotal point therefor, and means for guiding said binding-posts.
4. In a current-collector, a block of insulating material, brackets arranged on either side of the block, contact-blocks free for swinging movement in a horizontal plane and free to move vertically toward and from the brackets, thereby to permit the contacts to compensate for irregularities in the conductor and traffic-rails.
5. In a current-collector, contact devices, a

slot-bar supporting the same and free for vertical movement, a pair of telescopically-connected members of which one is connected to the slot-bar, and a spring tending to separate said members and impart downward stress to the slot-bar and contact devices.

6. In a current-collector, a slot-bar, contact devices carried thereby, a bracket depending from a car or other vehicle, a pair of telescopically-fitting members of which one is pivotally connected to the slot-bar and the other to the bracket, telescopic cups forming a spring-casing and secured one to each of the members, and a compression-spring disposed within said casing.

7. In a current-collector, a slot-bar, contact devices carried thereby, a bracket depending from a car or other vehicle, a hollow bar having pivotal connection with the bracket, a bar having pivotal connection with the slot-bar, the two pivoted bars interfitting telescopically and the hollow bar having a transversely-disposed opening, a cup carried by each bar, an adjustable supporting means for one of the cups, and a spring arranged between the cups, substantially as specified.

In testimony that we claim the foregoing as our own we have hereto affixed our signatures in the presence of two witnesses.

ABRAHAM A. SHOBE.
WILLIAM EMBLEY.
